Attorney.

UNITED STATES PATENT OFFICE.

EDWARD C. ZIPFEL, OF OMAHA, NEBRASKA.

TOY.

1,159,882.

Specification of Letters Patent.

Patented Nov. 9, 1915.

Application filed September 10, 1915. Serial No. 50,093.

To all whom it may concern:

Be it known that I, EDWARD C. ZIPFEL, a citizen of the United States, and a resident of Omaha, in the county of Douglas and 5 State of Nebraska, have invented certain new and useful Improvements in Toys, of which the following is a specification.

My invention relates to the general class of games and toys, and particularly to devices of this class employing balls or cups connected with a flexible or elastic cord.

It is the object of my invention to provide an article of this kind which will serve to induce mild exercise and the training of the 15 hand and eye to the performance of a somewhat difficult feat.

In the accompanying drawings Figure 1 is a perspective view of a device embodying my invention, showing the same in an inert 20 suspended position, Fig. 2 is a similar view showing the parts in the approximate position assumed at one phase of movement thereof, Fig. 3 is a view showing a further position of the parts, and Fig. 4 is a side 25 view, partially sectional, showing certain details of structure.

The article provided by my invention comprises, in a sense, two balls or spheres of which one is hollow and of such size that the 30 other may be inclosed thereby, the hollow ball being divided symmetrically to form two semispherical cups, and said cups and the integral ball being connected serially by a flexible and elastic member.

35 In the device illustrated, a ball 1 is secured upon one end of an elastic and freely flexible cord 2 which has at the opposite end a loop 3 or similar device by which said end of the cord may be detachably connected 40 with one of the fingers of a person's hand. The loop is preferably, though not necessarily, connected with the middle finger, as shown in Fig. 1.

The ball 1 may be of any suitable material 45 such as wood or rubber, and a convenient means for securing the same to the cord is shown in Fig. 4, there being a hole formed in the ball into which the end of the cord is inserted and secured by means of a plug 4

50 driven in alongside the cord.

At suitable intervals upon the elastic cord 2 are knots or beads 5 which serve to support the semispherical cups 6 and 7, each of the 55 cups having an axial perforation of such size that the cord will pass freely through the same while the knot or bead will not

pass through. The cups are made of moderately soft rubber, rubber composition, or other pliable and durable material capable of being distorted without injury thereto 60 and of returning to and maintaining a certain normal form when the distorting force is removed.

When the device hangs inert from the loop 3, the cups 6 and 7 both open downwardly, and the lower cup 6 should be at a distance above the ball 1 about equal to the diameter of the cup, while the upper cup 7 should be separated from the lower by approximately two diameters. When the portion of the cord between the cups is not under tension from the weight of the ball and the lower cup, the length of said cord 65 portion should be sufficient to enable the two cups to be faced together to form a hollow 70 ball, as shown in Fig. 3, without requiring the cord to be stretched or elongated.

In the use of the toy the loop 3 is slipped over the finger and the parts may at first either hang therefrom, as shown in Fig. 1, 80 or they may be gathered together with the ball partly contained in the lower cup, the cups nested together, and all retained by closing the fingers thereon. If started from the suspended position the parts may be set 85 in motion by raising the hand quickly so that the cord will be stretched by the increased tension thereon resulting from the inertia of the ball. Then, when the movement of the hand is stopped the cord will 90 return to its normal length, thus throwing the ball and cups up toward the hand so that they may be caught and held thereby. After catching the parts, or when they are started from the nested or grasped position, the 95 same are thrown downwardly with a certain force, such that after the cord has reached the limit of elongation it will pull the attached members rapidly upward and cause the return thereof to the hand. When the 100 various members are properly proportioned there is a tendency, during the upward movement, for the ball to overtake and strike the lower cup, and to turn or invert the same as indicated partially in Fig. 2. 105

By continuation of such movement the open sides of the two cups come together with the ball inclosed in the hollow sphere formed thereby, as shown in Fig. 3, and while in this position the parts may be grasped and 110 held in the hand until the downward throwing thereof is repeated.

By properly gaging the movements of the hand and the force with which the parts are thrown, the desired result of "catching the ball within the ball" may be frequently attained. It will be obvious, however, that a considerable degree of skill is required to consistently attain this result, and that the endeavors of the user to do so will result in a desirable exercise and training of the hands, arms and eyes. If desired, the difficulty of the exercise may be increased by casting or throwing the parts out horizontally, upwardly, or at various angles, instead of downwardly, or it may be required that the parts be caught with the cups nested together and the ball held within the lower cup, instead of being inclosed within the upper cup and the inverted lower cup.

The ball and cups may be colored or suitably decorated to give them an attractive appearance.

Now, having described my invention, what I claim and desire to secure by Letters Patent is:

1. In an article of the class described, a ball, a pair of semispherical cups, and a flexible cord connecting said ball and cups serially and connected therewith axially.

2. In a device of the class described, an

elastic cord having at one end a finger-engaging loop, a ball secured on the opposite end of the cord, and two semispherical cups supported on intermediate portions of the cord in spaced relation to each other and both opening toward the ball. 30

3. In a device of the class described, the combination with an elastic cord having finger-engaging means, of a ball and two cups carried on the cord, the cups being adapted to form a hollow sphere and inclose 40 the ball therein, and the ball and cups being normally in spaced relation to each other. 35

4. In a device of the class described, an elastic and freely flexible cord, a member fixedly connected with a part thereof, and elements connected with the cord in spaced relation to each other and to said member, said elements being adapted to inclose said member when brought into a certain relation thereto. 45

5. In an article of the class described, a flexible and elastic element, and members connected therewith in normally spaced relation to each other, certain of said members being formed and adapted to comprise an 55 inclosure for another when moved into determined relations thereto.

EDWARD C. ZIPFEL.
